UNITED STATES PATENT OFFICE.

SANFORD L. CLUETT, OF TROY, NEW YORK, ASSIGNOR TO CLUETT, PEABODY & CO., INC., OF TROY, NEW YORK, A CORPORATION OF NEW YORK.

FOLDER-BAR-CONTROLLING DEVICE.

Application filed October 21, 1921. Serial No. 509,383.

To all whom it may concern:

Be it known that I, SANFORD L. CLUETT, a citizen of the United States of America, and resident of Troy, in the county of Rensselaer and State of New York, have invented new and useful Improvements in Folder-Bar-Controlling Devices, of which the following is a specification.

This invention concerns folding and pressing machines such as are commonly employed in the commercial production of collars and cuffs and relates more particularly to improved means for imparting the proper operative movements to the folding devices.

15 In machines of this type, and as illustrated for example in the patent to Maitland et al, 713,230, November 11, 1902, the folder blades are mounted upon oppositely disposed pairs of aligned elongated blocks, each of

20 such blocks being actuated by means of a pair of cranks or eccentric pins. The employment of so large a number of cranks is undesirable mechanically, and in order to

25 reduce the number of these parts it has been proposed to connect adjacent ends of the blocks forming each of the bars by means of a slide member engaging aligned longitudinally extending guide slots in the blocks.

30 While the latter arrangement permits of reducing the number of cranks with a corresponding simplification of the driving mechanism, it is found in practice that the long slide member, when subjected to the wide

35 variation in temperature occurring in a machine of this type, tends to bind in its guide way, quickly resulting in mutual wear of the parts which necessitates frequent replacement not only of the slide member but also of the entire bar, while the oil re-

40 quired to lubricate the slide member is a source of frequent damage to the material operated upon. Moreover, the primary purpose in employing such a slide member is to maintain the two blocks comprising the

45 bar in endwise alignment; and this precludes any possibility of imparting relatively different movements to the outer and inner ends of each block, although when operating upon certain classes of work, a capability of the

50 mechanism to produce such action is highly desirable.

The principal object of the present invention is to provide for imparting movement to the folder blocks in a simple and mechan-

ically efficient manner and at the same time 55 to permit of adjustable variation in the relative motions of the outer and inner ends of each of such blocks.

In carrying this object into effect the invention may consist in pivotally connecting 60 adjacent ends of the blocks comprising the folder bar to a pair of links which in turn are pivoted to a relatively fixed support. The lengths of such links and their fixed pivots may be so chosen as to provide with- 65 in reasonable limits for any desired movement of the inner ends of the blocks relatively to that imparted to their outer ends by their actuating eccentric pins. By this arrangement it is evident that pivotal connections have been substituted for reciprocating parts in uniting the blocks, with resultant increase in mechanical efficiency and length of service, while at the same time providing for differential movements of the inner and outer ends of the blocks.

To permit of varying the degree of relative movement of the extremities of the folder blocks, the pivot pins for securing the links thereto may be mounted upon 70 slides which are adjustable longitudinally of the respective blocks, while if desired the opposite ends of the respective connecting links may be pivoted upon a common member 75 capable of adjustment in a direction transverse of the length of the blocks.

In accordance with a proposed modification, cams may be substituted for the links in guiding the inner ends of the folder blocks, such cams having the proper configuration for imparting the desired movement either circular or non-circular to the bars. Such cams may also be arranged for adjustment relatively to the fixed frame of 90 the machine whereby their action in guiding the bars can be changed at will and for securing a further variation in movement the cam followers may be adjustable lengthwise 95 of the bars.

With either of the above described arrangements it is possible to vary both the transverse and the longitudinal throw of the folder bars through a wide range, which makes it possible to employ the machine in folding a much wider variety of work than 100 has heretofore been practicable with machines of this character.

In the accompanying drawings there is

exemplified means suitable for use in carrying the present invention into effect and in such drawings:—

Fig. 1 is a plan view of a folding and pressing machine of usual type and having the present invention applied thereto, the parts being shown in the position which they occupy at the beginning of the folding operation;

10 Fig. 2 is a view similar to Fig. 1, certain parts being broken away, and illustrating the mechanism in the position which it occupies at the completion of the folding operation;

15 Fig. 3 is a partial front elevation of the machine showing the die plate as elevated.

Fig. 4 is an end elevation of the machine as shown in Fig. 3;

20 Fig. 5 is a transverse vertical cross section to large scale through the bed plate of the machine;

25 Fig. 6 is a fragmentary plan view to large scale illustrating a modified form of mechanism;

30 Fig. 7 is a front elevation of the parts shown in Fig. 6; and

35 Fig. 8 is a fragmentary plan view illustrating a further modification.

The machine herein disclosed may be of a general type of that illustrated in the patent to Brown 1,053,477, February 18, 1913 and the moving parts of the same may be actuated in the manner therein disclosed or in any other suitable way. The frame of the machine is shown as comprising the legs 1, 2 and the table-like support 3. The member 3 is provided with a longitudinally extending recess for the reception of the bed plate 4 upon which the material is placed for folding. Brackets 5 are secured to the rear of the frame, and to such brackets is pivoted the arm 6 which supports the die plate 7. Cooperating with the die plate 7 are the folder blades 8, 9 such blades being carried by pairs of substantially aligned and independent folder blocks 10, 11 and 12, 13 respectively. These folder blocks rest upon the upper surface of the table 3 and are guided and held in operative position with respect thereto by means of members such as 14, 15, 16 respectively. As the blocks 10, 11 and 12, 13 are substantially alike and actuated in the same manner, it will be necessary to refer in detail to the parts associated with the blocks 10, 11 only, it being understood that similar mechanism is employed in connection with the other blocks 12, 13.

The remote ends of the blocks 10, 11 are each provided with a bracket 17, 18 respectively such brackets being furnished with suitable journal openings for the reception of cranks or eccentric pins 19, 20 respectively mounted upon the upper ends of vertical shafts 21, 22. These shafts may be actuated as set forth in the patent to Brown

above referred to, or in any other suitable manner.

As indicated in Fig. 1, the pins 19, 20 occupy the position which they assume at the beginning of the folding operation, the shafts turning during such operation in the direction indicated by the arrows of this figure. With this arrangement it is evident that the remote ends of the blocks 10, 11 are constrained to move in predetermined paths 75 of arcuate form.

The adjacent ends of the blocks 10, 11 are provided with longitudinal slots 23, 24 respectively, and within the respective slots are arranged slides 25, 26 which may be secured in adjusted position relatively to the blocks by means of screws or bolts 27, 28. Secured in the adjacent ends of the slides 25, 26 are vertically projecting pivot pins 29, 30 respectively, upon which are pivoted 80 the inner ends of a pair of link members 31, 32. The outer ends of the link members are pivotally secured by means of pins 33, 34 respectively to a plate 35. This plate is provided with a slot 36 and may be adjustably secured to the table of the machine by means of a bolt 37. In the arrangement just described the length of the crank arm of which pin 20 forms the crank is less than that of the link 32. As so constructed, rotation of the shaft 22, for example, serves to move the block 11 both transversely toward the center of the machine and also longitudinally, but by reason of the difference in the lengths of the crank arm and 100 link 32, the motion imparted to the two ends of the block will be different. Such movement is advantageous in securing the proper action of the folding blade, in wiping the edge of the material over the die plate, and in certain classes of work is necessary to produce the best results. The links 31, 32 however, are so arranged that they may readily be removed and be replaced by links of different lengths so that it is possible by 105 interchanging such links to secure any desired variation in the movement of the block.

Furthermore by adjustably connecting the links to their respective folder blocks, differences in movement of the two blocks may be secured, while the transverse adjustment of the plate 35 provides a simultaneous change in the initial position of the blocks 10 and 11 such as may be desirable under certain circumstances.

Referring to Figs. 6 and 7, the supporting table is indicated at 38, having mounted thereon the folder blocks 39, each of such blocks being provided with a slot 40 for the reception of a slide member 41. This slide member is adjustably retained within the slot by means of a bolt such as 43. At their outer extremities, the slide members 41 are furnished with pivot pins 44 upon which are journaled the cam follower rolls 110

45. Each of these rolls is adapted to engage a cam surface 46 formed upon a cam block 47. This block may if desired be fixed to the supporting table, but is preferably provided with a slot such as 48, whereby it may be adjustably secured to the table by means of a bolt 49. A plate 50 is secured to one face of the block 47 by means of a screw 51 and this plate serves for the attachment of one end of a spring 52, whose other end is connected to the folder block 39. This spring thus serves to maintain the roll in engagement with the cam surface of the block 47.

15. It being assumed that the other end of the block 39 is actuated by means of an eccentric pin or crank in the manner illustrated in Fig. 1, the movement imparted to the block by such crank or pin will be modified by the travel of the roller 45 over the cam surface of the block 47. This cam surface may be of any desired configuration and, as it is evident that the cam block may be interchangeable with other cam blocks 25 having different cam surfaces, it is clear that the path of movement of the inner end of the folder block may be varied within very wide limits. It is also evident that the adjustable mounting of the block serves further to increase the range of variation in movement of the folder block.

In Fig. 8 is shown a still further modification wherein the table 53 serves to support the folder block 54. This block is provided with a longitudinal slot 55 in which is supported a slide member 56 adjustably held in position by means of the bolt 57. At its inner end this slide is provided with a pin 58 upon which is journaled a roll 59 which engages within a cam slot 60 in a block 61. This cam block is also preferably arranged for adjustment, as by means of the slot 62 and the bolt 63, whereby the movement of the folder block 54, as determined by the cam groove 60, may be varied at will.

While in the above description reference has been had to several specific arrangements by means of which the relative movements of the opposite ends of the folder block may be predetermined and adjusted at will, it is contemplated that other means might well be devised for attaining the same result, and it is to be understood that any equivalent means whereby this result is attained may fall within the scope of the present invention.

Having thus described the invention in a preferred embodiment of the same together with the mode and use thereof, what I claim and desire to secure by Letters Patent of the United States is:

60. 1. A machine of the class described comprising an elongate folder block, means for moving one end thereof, a member adjust-

able longitudinally of said block adjacent its opposite end, and means engaging said adjustable member for guiding said last named end of the block.

2. A folding machine comprising a folder block, means for moving one end of said block in an arcuate path, a member engaging a part carried by the opposite end of the block, and means for adjusting said member in a direction transverse of the length of said block.

3. A folding machine comprising an elongated folder block, eccentric means for moving one end of said block in a fixed path, and means for guiding the opposite end of said block, said means comprising elements respectively adjustable longitudinally and transversely of the block.

4. A folding machine comprising a movable folder block and means for moving and guiding said block, said means comprising a pair of arms engaging said block at separated points, the point of engagement of one of the arms with the block being adjustable longitudinally of the block.

5. A machine of the class described comprising a frame and a pair of folder blocks movable relatively thereto, independent elements having adjustable connection with the respective blocks, and a member adjustable relatively to the frame and engaging both of said elements.

6. A folding machine comprising a folder block, a crank for imparting movement to one end of the block, a link connected to the block adjacent to its other end, the point of connection of the link to the block being adjustable longitudinally of the block, and a normally fixed pivot for the other end of the link, said crank being of less length than the link.

7. A machine of the class described comprising a folder block, eccentric means for imparting movement to one end of the block, a slide member adjustable longitudinally of the other end of the block, a link pivotally secured to said slide member, and a normally fixed, adjustable element having pivotal connection with the opposite end of the link.

8. A folding machine comprising a support, a pair of substantially aligned folder blocks movable relative thereto, eccentric means for moving the remote ends of said blocks in opposite directions, a slide member adjustable longitudinally of each block at the adjacent ends thereof, a link pivotally secured to each slide member, a plate adjustably secured to the support for movement transversely of the length of the folder blocks, and pivotal connections between said links and said plate.

Signed by me at Troy, Rensselaer County, N. Y., this 19 day of October, 1921.

SANFORD L. CLUETT.
